UNITED STATES PATENT OFFICE.

DAVID PETRI-PALMEDO, OF BRIDGEPORT, CONNECTICUT, ASSIGNOR TO ELECTRIC COMPOSITOR COMPANY, OF BRIDGEPORT, CONNECTICUT, A CORPORATION OF NEW JERSEY.

MATRIX-MAGAZINE.

1,112,653.

Specification of Letters Patent.

Patented Oct. 6, 1914.

Application filed November 17, 1913. Serial No. 801,332.

To all whom it may concern:

Be it known that I, DAVID PETRI-PALMEDO, a citizen of the United States, residing at Bridgeport, in the county of Fairfield and State of Connecticut, have invented a certain new and useful Improvement in Matrix-Magazines, of which the following is a full, clear, and exact description.

This invention relates to the lower delivery end of a matrix magazine which is adapted for use in a linotype machine. Each matrix magazine contains a plurality of channels for holding the matrices; and, associated with each channel, is an escapement mechanism, which must be operable from the key board, for controlling the release of matrices therefrom. The escapements, whatever may be their specific form, are delicate little pieces of mechanism; and the mounting of these escapements in operative position relative to the several magazine channels, near the lower delivery mouths thereof, has heretofore been a delicate, difficult and expensive operation, and the repairing of these escapements has been likewise difficult and expensive.

The object of this invention is to provide a construction which will permit the escapements to be assembled in operative positions easily and inexpensively,—which will facilitate repair or replacement of escapements when required, and which will permit the use of a very efficient specific form of escapement mechanism.

In the present invention the lower or delivery end of the back wall of the magazine is of a plurality of metal blocks, set side by side, and locked in place, said blocks having in corresponding sides recesses which serve as housings, each adapted to house an escapement mechanism, which housings will each be covered by the next adjacent block. This constitutes the fundamental novel characteristic of this invention, which, however, includes additionally numerous specific features of construction, as shown in the drawing and hereinafter described and definitely pointed out in the appended claims.

In the drawing, Figure 1 is a perspective rear elevation of a matrix magazine embodying the invention. Fig. 2 is a horizontal section of a part of a magazine in the plane indicated by line 2—2 on Fig. 4.

Fig. 3 is a horizontal sectional view of the right end of a magazine in the plane indicated by line 3—3 on Fig. 4. Fig. 4 is a transverse vertical section of the lower part of a magazine, which section is in a plane indicated by line 4—4 on Fig. 3. Fig. 5 is a perspective view of one of the metal blocks which carries an escapement mechanism; and Fig. 6 is a vertical sectional view, the sections being taken on the broken line 6—6 on Fig. 4.

The front wall of a magazine may consist of a plate A of suitable height and width, having in its rear face a plurality of vertical grooves a. The upper part of the back wall of each magazine may consist of a plate C which is parallel with the plate A and has in its front face vertical grooves so placed that each lies directly behind a groove a and forms, with it, a magazine channel. The ears m on a matrix M project into these grooves a and c, and thereby the matrices are guided. These front and back plates are connected by end plates P, and are held properly spaced apart by vertical bars p placed at suitable intervals.

The plate C does not extend to the bottom of the magazine as does the front plate A; but below the lower edge of the back plate C are a plurality of metal blocks, B, B¹, set side by side, as shown, so as to form the lower part of the back wall of the magazine.

One face of each block, (the right face as shown) is recessed,—the recess b extending to the front edge and to the lower edge of this block. When two of these blocks are placed side by side, the right hand block serves as a cover for the recess in the other block, thereby forming a housing within which the escapement mechanism is mounted.

The front edge of each block is vertically rabbeted as shown so as to form a two sided groove b². The third side of the groove is formed by the adjacent block; and these blocks are placed so that these grooves b² are downward continuations of the groove c. Each groove A and the opposed grooves c, b, form therefore a magazine channel in which the matrices M are guided by the projection of their ears m into said channel.

The magazine also includes a horizontal back bar N upon which the blocks B are

secured, so that when this back bar N is secured in place the blocks B, B¹ will occupy the stated positions. This back bar is secured to the rear side of the lower edge of the back member C by means of screws n. The blocks B¹ are fixed at intervals to the front face of the back bar. In the front face of the back bar N there is a horizontal groove n¹ extending from one end to the other thereof. In the rear edges of the blocks B, B¹ are the grooves b⁴, which grooves, when the blocks are properly assembled, are alined and receive the locking bar S. In the front edges of the blocks B, B¹ are also cut the grooves b⁵. When the blocks are properly assembled all of these grooves will be in alinement, and a locking bar T will be pushed into these grooves, as shown in Fig. 4. The various blocks B are made of the required thickness so that a number of them placed side by side, as stated, may be snugly inserted into the space between two fixed blocks B¹, or between a fixed block and an end plate P of the magazine. When they have been so placed, the described locking bars are put in and then the back bar is secured to the magazine. The front edges of the blocks B, B¹ are rabbed at their upper ends, thereby forming recesses b⁶ which receive the lower edge e² of plate C; and thereby forward movement of any block is provided. To repair an escapement it is only necessary to remove the back bar and take out the locking bars, and then to pull out the block whose escapement needs repairing.

As before stated in each of the recesses formed in the right face of a block B or B¹ an escapement mechanism is mounted. The particular escapement mechanism shown consists of a star wheel E, two detent levers F, G, an operating lever H, and a rebound preventing dog J. These are mounted on studs fixed to the bottom or left wall of the recess and projecting longitudinally to the right therefrom,—said studs being indicated respectively at 1, 2, 3, 4, 5. The stud 1 is so located that arms of the star wheel may project through the open front of the recess b into the groove b² in the front edge of the block in which the recess is formed, and thereby into the path of the ears of matrices which project into said groove. The stud 4 is so located that one arm of the operating lever H will project down out of the open bottom of the recess, so that it may be engaged by an operating device, as, for example, the lever L. Each of these levers L may lie above a reed L¹ of the sort commonly used in linotype machines for transmitting motion from a key to an escapement mechanism. The rotation of the star wheel is normally prevented by the engagement with one of the arms of the star wheel of a roller bearing stud f mounted on the end of

the lever F. Another roller bearing stud g mounted on the lever G lies normally out of the path of the star wheel arms; but when the stud of lever F is moved out of engagement with a star wheel arm, the stud of lever G is moved into the path of that arm so as to stop the star wheel in an intermediate position. The reciprocal movement of these two levers F and G is produced by means of an arm f¹ on lever F which engages in a notch g¹ in lever G. A spring K normally holds these two levers in the positions shown. An arm h of the operating lever H engages in a notch f² in the end of lever F. Obviously when lever L presses up on the arm of the operating lever H, lever F will be withdrawn from the path of a star wheel arm, and lever G will be moved into the path of said arm. When the star wheel is released the weight of the matrix column will cause it to turn in the direction of the arrow thereon, and thereby the lowest matrix will be released from the restraining influence of the star wheel arm which was engaging it, while the next arm of the star wheel will move into the path of the upper ear of the next matrix and stop it in its descent. When the lever L is allowed to descend the parts return to the position shown. That is to say, the lever G is moved out of engagement with a star wheel arm, and the lever F is moved into the path of a star wheel arm. As this is done the star wheel moves from the intermediate position in which it was stopped around to the position shown in the drawing, in which it will be stopped by the engagement of its arms with lever F, and thereby the star wheel is stopped.

The studs 1 to 5, inclusive, extend to the right until they substantially engage the left face of the adjacent block. The star wheel and the rebound preventing lever J which is mounted on stud 5, are substantially as thick as the recess b is deep, and therefore they cannot move along their studs out of operative position. The roller bearing studs f, g project so that they lie close to the opposed face of the next block, and therefore levers F and G cannot move on their studs out of operative position. Lever H may be made with a thick hub h² so that it can have no substantial sidewise movement on its stud and must therefore remain in operative position.

Having described my invention, I claim:

1. A matrix magazine having for the lower part of its rear wall a plurality of metal blocks set side by side and locked against relative displacement, each of said blocks being cut away in one side to form a recess for the escapement mechanism of a magazine channel.

2. A matrix magazine having a vertically grooved front wall, and a vertically grooved

rear wall, the lower part of which is made up of a plurality of blocks set side by side and locked against relative displacement, each block having a vertical groove in its 5 front face and a recess in one side, and escapement mechanisms located one in each recess and mounted on the block in which said recess is formed.

3. A matrix magazine having a vertically grooved front wall and a vertically grooved 10 rear wall, the lower part of which is made up of a plurality of blocks set side by side and locked against relative displacement, each block having in one side a recess which 15 extends to the front and lower edges of the block, and an escapement mechanism in each recess mounted on the block in which said recess is formed.

4. A matrix magazine, the lower part of 20 whose rear wall is composed of a plurality of metal blocks secured side by side, each block having in one side a recess, studs fixed to the bottom of each recess and extending therefrom toward and close to the face of 25 the adjacent block, and escapement mechanisms, the parts of which are mounted on said studs.

5. A matrix magazine, the lower part of 30 whose rear wall is composed of a plurality of metal blocks secured side by side, each block having in one side a recess, studs fixed to the bottom of each recess and extending therefrom toward and close to the face of 35 the adjacent block, a star wheel, two reciprocally acting restraining levers for engaging arms of the star wheel, and an operating lever, said star wheel and levers being mounted on said studs.

6. A matrix magazine, the lower part of 40 whose rear wall is composed of a plurality of metal blocks secured side by side, each block having in one side a recess, studs fixed to the bottom of each recess and extending therefrom toward and close to the face of 45 the adjacent block, a star wheel and two reciprocally acting restraining levers for engaging the arms of the star wheel, said levers and star wheel being mounted upon 50 said studs, and means accessible through the bottom of each recess for moving said restraining levers.

7. A matrix magazine having a grooved front wall, a vertically grooved rear plate which does not extend down as far as the lower edge of the front plate, a back bar 55 removably connected with said back plate, a plurality of blocks removably secured to the front face of said back plates, all of said blocks having recesses in corresponding sides, and escapement mechanisms in said 60 recesses.

8. A matrix magazine having a grooved front wall, a vertically grooved rear plate which does not extend down as far as the lower edge of the front plate, a back bar 65 removably connected with said back plate, a plurality of blocks removably secured to the front face of said back plates, all of said blocks having recesses in corresponding sides, escapement mechanisms in said 70 recesses, said back plate having in its front face a horizontal groove, and said blocks having in their rear edges horizontal grooves which together with the groove in the back plate form a hole to receive a locking bar, 75 and a locking bar fitted to said hole.

9. A matrix magazine having a grooved front wall, a vertically grooved rear plate which does not extend down as far as the lower edge of the front plate, a back bar 80 removably connected with said back plate, a plurality of blocks removably secured to the front face of said back plate, all of said blocks having recesses in corresponding sides, escapement mechanisms in said 85 recesses, said back plate having in its front face a horizontal groove, and said blocks having in their rear edges horizontal grooves which together with the groove in the back plate form a hole to receive a locking bar, 90 and a locking bar fitted in said hole, and said blocks having notches in their front edges, and a locking bar engaging all of the notches in the front edges of said blocks.

In testimony whereof, I hereunto affix 95 my signature in the presence of two witnesses.

DAVID PETRI-PALMEDO.
